CLAIM

The ornamental design for a tool bit, as shown and
described.

DESCRIPTION

FIG. 1 is a front perspective view of a tool bit showing my
new design according to a first embodiment;
FIG. 2 is a bottom plan view thereof;
FIG. 3 is a top plan view thereof;
FIG. 4 is a right side elevation view thereof;
FIG. 5 is a left side elevation thereof;
FIG. 6 is a front elevation view thereof;
FIG. 7 is a rear elevation view thereof;
FIG. 8 is an enlarged view of portion 8 encircled in FIG. 1;
FIG. 9 is a front perspective view of a tool bit showing my
new design according to a second embodiment;
FIG. 10 is a bottom plan view thereof;
FIG. 11 is a top plan view thereof;
FIG. 12 is a right side elevation view thereof;
FIG. 13 is a left side elevation thereof;
FIG. 14 is a front elevation view thereof;
FIG. 15 is a rear elevation view thereof;
FIG. 16 is an enlarged view of portion 16 encircled in FIG.
9;
FIG. 17 is a front perspective view of a tool bit showing my
new design according to a third embodiment;
FIG. 18 is a bottom plan view thereof;
FIG. 19 is a top plan view thereof;
FIG. 20 is a right side elevation view thereof;
FIG. 21 is a left side elevation thereof;
FIG. 22 is a front elevation view thereof;
FIG. 23 is a rear elevation view thereof;
FIG. 24 is an enlarged view of portion 24 encircled in FIG.
17;
FIG. 25 is a front perspective view of a tool bit showing my
new design according to a fourth embodiment;
FIG. 26 is a bottom plan view thereof;
FIG. 27 is a top plan view thereof;
FIG. 28 is a right side elevation view thereof;
FIG. 29 is a left side elevation thereof;
FIG. 30 is a front elevation view thereof;
FIG. 31 is a rear elevation view thereof; and,
(Continued)

FIG. 32 is an enlarged view of portion 32 encircled in FIG. 25.

The dashed broken lines in the drawings encircle portions of the claimed design that are illustrated in enlargements and form no part of the claimed design.
